(57) **CLAIM**

I claim the ornamental design for a table, as shown and described.

DESCRIPTION

FIG. 1 is a top perspective view of a table in an extended configuration showing my new design;

FIG. 2 is a top view thereof;

FIG. 3 is a right side view, the left side being a mirror image thereof;

FIG. 4 is a bottom view thereof;

FIG. 5 is a frontal view, the rear view being a mirror image thereof;

FIG. 6 is top view of my table design showing a retracted configuration of FIG. 2;

FIG. 7 is a right side view showing a retracted configuration of FIG. 3, the left side being a mirror image thereof;

FIG. 8 is a bottom view showing a retracted configuration of FIG. 4; and,

FIG. 9 is a frontal view showing a retracted configuration of FIG. 5, the rear view being a mirror image thereof.
